REPEATING PHONOGRAPH

Application filed May 28, 1928. Serial No. 281,136.

This invention relates to an apparatus for playing a plurality of records or to that type of phonograph which has an automatic record changer organized therewith.

- 5 One of the principal objects of the present invention is to provide an apparatus of this character which, while of compact construction and well adapted to be completely housed in the usual forms of cabinets, is
 10 capable of handling and automatically and successively playing a relatively large number of records. Thirty or more records may be handled and successively played and of course any lesser number may be utilized.
 15 The machine first plays one side of each of the records and then the other sides thereof. Along with these advantages, the bank of records is so positioned and the records are so handled that all of the records except the
 20 one being played are concealed within the cabinet and yet there is a minimum interval between the playing of the records.

Another important object resides in the provision of a machine of this character
 25 which positively handles and controls the records throughout all of their transfer movements and this without subjecting the records to any injurious or destructive forces. During all transfer movements the records
 30 are positively gripped and transported.

Another object of the invention resides in the co-ordination and organization of the various instrumentalities of the machine whereby the several operations are properly
 35 controlled and synchronized and are automatically carried out.

A further object is to provide a machine of this character and having these advantages and which is of simple and durable
 40 construction, reliable and effective in operation and easy and comparatively inexpensive to manufacture.

In general the machine comprises suitable record playing means, a storage station for
 45 the bulk of the records, transfer means for taking a record from the storage station and transferring it to the record playing means and vice versa, a system of controls whereby the transfer means and the record playing
 50 means are started and stopped automatically

at the proper times, and various auxiliary appurtenances which facilitate and insure proper operation of the major elements as will be hereinafter more fully described.

In accordance with the present invention 55 the record playing means may comprise a motor driven turn table with which suitable sound reproducing mechanism coacts. The sound reproducing mechanism includes the usual horizontally swinging arm which, in 60 the present instance, is also mounted for vertical movement. This arm carries the usual mechanical reproducer or if electrical reproduction is to be employed carries the usual microphone connected in any suitable way 65 to the amplifying means.

The storage station for the records underlies the turn table and its motor and comprises an endless storage rack made up of an endless belt trained around suitable rollers 70 and having a plurality of parallel transversely extending strips fastened thereto and defining pockets for receiving and supporting the records.

As indicated, the transfer means takes a 75 record from the storage rack, carries it up to and deposits it on the turn table and simultaneously it takes a record from the turn table and returns it to the storage rack. Preferably, this transfer means comprises a 80 pair of endless and flexible transfer carriers or members such as chains, or the like, which are so mounted as to extend along the opposite sides of the turn table and also to extend to the receiving and discharge ends of 85 the storage rack. On these endless flexible elements or chains spaced sets of grippers are carried, the grippers preferably consisting of spring clips designed to embrace and grip the edges of the records. At the receiving and discharge ends of the storage rack and adjacent the turn table, cams are provided and are located and designed to coact with the clips to open the clips at the proper times whereby the clips are adapted to engage and release the records.

The transfer chains are driven from an electric motor through suitable reduction gearing and whenever the transfer chains are driven the spring motor which actuates the 100

turn table is rewound by virtue of the provision of gearing between the transfer drive and the spring motor, this winding gearing having a slip clutch incorporated therein to preclude excessive winding and consequent injury to the spring motor.

A main automatic switch is incorporated in the controlling circuit of the electric motor employed to drive the transfer means and this switch is opened and closed under the influence of the sound reproducing mechanism so that, when the sound reproducing mechanism completes the playing of a record, it automatically closes this switch and starts the motor thereby driving the transfer chains. A controlling cam is driven in synchronism with the transfer chains and as soon as these chains start to move the cam is actuated and a train of mechanism is set in motion to automatically apply the brake governing the motion of the turn table and to actuate means provided for lifting the arm of the sound reproducing mechanism. This stopping of the turn table and the lifting of the reproducer occurs just prior to the engagement of the adjacent set of clips with a record on the turn table inasmuch as these clips must move off their cams before they can engage the record. The record having been engaged is carried along with the chains back to the receiving end of the storage rack. Simultaneously, a new record is transferred from the storage rack to the turn table and when the new record is deposited on the turn table, a lug on one of the transfer chains engages a projection on the tone arm of the reproducer to reposition the reproducer, that is, to swing it over to initial playing position. As the reproducer reaches initial playing position it again actuates the main automatic switch to shut off the electric motor and stop the transfer drive. At this time the main cam has completed a revolution and operates its associated train of mechanism to release the turn table and to permit the reproducer to lower. The record is then played and upon completion of the playing of the record this cycle of operation is repeated.

Incorporated in the circuit with the main automatic switch described is a manually operable switch which is utilized for starting and stopping the machine. In order to prevent the spring motor from running down in the event the manually operable switch is opened to stop the machine during the playing of a record and also for the purpose of insuring positioning of the parts for immediate resumption of the automatic operation upon subsequent closing of the manually operable switch, a shunt path is provided in the transfer motor circuit around the manually operable switch and has an auxiliary automatic switch incorporated therein. This auxiliary automatic switch includes a pair of normally closed contacts and an operating

device controlled by lugs on one of the transfer chains for opening the normally closed contacts of the auxiliary automatic switch whenever a record is brought up to a position adjacent the turn table.

As long as the manually operable switch is closed, the auxiliary automatic switch, irrespective of whether it is opened or closed, has no effect on the operation as it merely controls a shunt path around the closed manually operable switch, but when the manually operable switch is opened, the auxiliary automatic switch and the main automatic switch act conjointly to complete the transfer motor circuit when both are closed. However, with the manually operable switch open, both automatic switches must be closed to cause operation of the transfer motor as, if either automatic switch is opened, the transfer motor circuit is broken.

With this arrangement, if the manually operable switch is opened while a record is being played, the playing of the record continues until the record has been completely played. Upon completion of the playing of the record, the contacts of the main automatic switch are closed by the sound reproducing mechanism, and as the contacts of the auxiliary automatic switch are normally closed (and are closed at this time), the transfer motor circuit is completed and the played record is picked up from the turn table and carried toward the receiving end of the storage station while a new record is being advanced from the discharge end of the storage station toward the turn table. This has also actuated the main cam and caused application of the turn table brake and elevation of the reproducer. As the new record approaches a position immediately adjacent the turn table, a lug on one of the transfer chains or on one of its grippers, engages the operating device for the auxiliary automatic switch and opens the auxiliary automatic switch thereby breaking the transfer motor circuit and stopping the new record in a position immediately adjacent the turn table.

In this position of the new record, the lug on one of its grippers has not advanced so far as to reposition the reproducer and open the main automatic switch and consequently upon subsequent closing of the manually operable switch, the transfer motor circuit is completed, and the new record advanced the slight distance necessary to deposit it on the turn table and to reposition the reproducer thus opening the main automatic switch and breaking the transfer motor circuit.

When a record has been carried from the discharge end of the storage station to the turn table and back to the receiving end of the storage station it is reversed so that the next time that it is brought back to the turn table its opposite face is presented for playing. Due to this feature and to the fact that

a relatively large number of records may be handled the machine can play continuously for hours without repeating any record.

Each time a record is deposited on the turn table it is automatically centered thereon by virtue of the action of a pair of centering fingers cooperably disposed with respect to the turn table and operated automatically from one of the transfer chains. The passage of the record to its proper position over the turn table and over the center pin thereof is facilitated and insured by virtue of the provision of a vertically movable top which is elevated during the transferring of the records but which is automatically lowered under the control of the main cam when a record is deposited on the turn table and is being played.

During each record transferring operation the storage rack is automatically advanced to feed the records to the discharge end of the storage station and to position them successfully in cooperative relation to the clips which pick the records up and carry them onto the turn table.

Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a view in end elevation showing the machine embodying the present invention with the cabinet omitted for the sake of illustration;

Figure 2 is a plan view of the parts shown in Figure 1, the shifttable top being omitted to permit of illustration of the underlying parts;

Figure 15 is a fragmentary view partly in side elevation and partly in central vertical section illustrating the action of the separating and guiding finger for the records returned to the storage rack, the adjacent parts being omitted for the sake of simplicity in illustration; and

Figure 16 is a fragmentary perspective view showing the means employed for disengaging each of the spring clips from the record when the latter is to be deposited on the turn table.

General frame construction

Any suitable frame construction may be employed but, for the sake of example, one type of construction is shown. Referring more particularly to Figures 1 and 2, the numeral 1 designates a base plate which may be mounted in a suitable cabinet (not shown) and which supports a pair of spaced U-shaped brackets 2 fastened to the plate 1 by screws 3. The legs 4 of the brackets 2 extend vertically and are fastened to longitudinal supporting bars 5. Transversely extending cross rods 6 are mounted on these bars 5 and support side plates 7 and 8, the side plates being held in proper position by means of spacing sleeves 9 fitted on the rods and interposed between the plates 7 and 8 and the bars 5 and by means of nuts 10 threaded on the ends of the cross rods 6 and bearing against the plates 7 and 8.

The upper ends of the side plates 7 and 8 are held in proper spaced relation by means of cross rods 11 which may be shouldered or equipped with spacing sleeves and which have their ends projecting through openings in the side plates 7 and 8 and receiving nuts 12 which bear against the side plates.

Sound reproducing means

A cross plate 15 extends transversely between and is supported on the side plates 7 and 8 and this cross plate carries a bracket 16. The bracket 16 and plate 15 are provided with bearings in which a turn table spindle 17 is rotatably fitted, the spindle carrying a turn table 18. The upper end of the spindle projects above the turn table to provide the usual center pin. On the bracket 16 a spring motor 19 of conventional construction is mounted and drives the spindle 17 through intermeshing gears 20 (see Figure 1). The sound reproducing mechanism also includes a swingable arm 21, which may carry the

usual mechanical reproducer 22 or a microphone if electrical reproduction is employed. The arm 21 is hollow to provide the tone arm for the reproducer 22 and is swiveled as at 23 on a supporting fitting 24 having trunnions 25 rotatably fitted in the bearings provided therefor in a bracket 26 secured to the adjacent side plate 8. With this construction the reproducer may not only swing horizontally to traverse the record but may be also tilted vertically to move the reproducer and its stylus toward and away from the record. The fitting 24 may be connected with a suitable amplifier which may be built into the cabinet or if electrical reproduction is utilized the reproducer employed may be appropriately connected to a remotely located amplifying unit.

The record storage station

20 The storage station underlies the turn table and its drive and consists of an endless storage rack designated generally at 30 and made up of an endless belt 31 (see Figure 8) trained about rollers 32 having shafts or trunnions 33 rotatably mounted in bearings provided therefor in the longitudinal supporting bars 5. At close intervals throughout the length of the belt 31 transversely extending strips 34 are provided and are arranged parallel to each other, the strips 34 being fastened to the belt in any suitable manner as for instance by screws 35 (see Figure 9) which passes through the belt and screw into the strips 34, the heads 35 of the screws abutting washers 36 between these heads and the underside of the belt 31. The upper run of the storage rack is the only part thereof that carries the record and it is prevented from sagging and otherwise 40 properly supported by virtue of the provision of a track 37 extending between the rollers 32 and supported on the bars 5. This track 37 has grooves 38 to accommodate the heads of the screws 35 and the washers 36 and it also 45 has a longitudinal slot 39 extending entirely therethrough and part way of its length and communicating with longitudinal grooves 39^a extending only part way therethrough but the full length of the track and all serving 50 a purpose which will be hereinafter more fully described.

Record transfer means

Transfer means is provided for taking the 55 records one at a time from the storage rack and transferring them to the turn table and simultaneously taking the record on the turn table that has just been played and carrying it back to the storage rack.

60 This transfer means comprises a pair of similar transfer chains designated at 41 and 42 arranged adjacent to the side plates 7 and 8, respectively, and trained about sprocket wheels 43, 44, 45 and 46, and 43', 44', 45' and 65 46', respectively. These sprocket wheels are

fixed on shafts 47 rotatably mounted in the side plates 7 and 8 adjacent the corners thereof. As indicated, the sprocket wheels are arranged at the corners of the side plates and project beyond the same so that the several 70 runs of the sprocket chains are located beyond the edges of the side plates.

Spaced sets of grippers are carried by the sprocket chains 41 and 42 and in the present instance four sets of grippers are provided, 75 each set of grippers consisting of a pair of spring clips with one member of each pair fastened to the chain 41 and the other member of each pair fastened to the chain 42. The members of each pair of grippers are 80 located exactly opposite to each other. The grippers of one set are designated at 50 and 50' and of the other sets at 51 and 51', 52 and 52', and 53 and 53'.

The grippers are all of identical construction and each comprises a resilient body portion 54 suitably fixed to gripping arms 55 and tending to urge the gripping arms 55 toward each other. One of the gripping arms 55 is extended as at 56 and fastened to the transfer chain of which it is an associate. The other gripping arm also has an extension 57 with beveled or deflected side portions designed to coat with the controlling cams which will now be described.

As shown in the drawings the storage rack is disposed below the turn table and the upper runs of the transfer chains extend along the opposite sides of the turn table, the vertical runs of the transfer chains extend past the opposite ends of the storage rack, and the return runs of the transfer chains extend along and below the storage rack. One end of the storage rack receives the records returned from the turn table and such receiving end is the right hand end, as shown in Figures 2 and 4, while the opposite end of the storage rack constitutes the discharge end thereof. As indicated, parallel runs of the transfer chains straddle both ends of the storage rack and at each end the parallel runs of the transfer chains are located opposite or in the same vertical plane as the end pocket defined by the two transverse strips located above the end roller. Thus, at the discharge end of the storage rack the runs of the transfer chains parallel the end pocket and as the grippers 50 and 50' move up with these runs they are positioned opposite this end pocket.

At this time these grippers 50 and 50' are automatically opened by cams 60 integrally formed with or suitably fixed to the adjacent ends of the side plates 7 and 8 and coacting with the operating arms 57 of the clips 50 and 50'. To prevent the clips from moving bodily under the influence of the cams and thus twisting the chains, guide rails 61 are provided to engage the arms 56, the guide rails being located opposite the ends of the side plates and being rigidly supported there-

on by means of brackets 62 and reinforced by cross members 63.

At the receiving end of the storage rack a similar arrangement is provided and comprises cams 65 coacting with the arms 57 of the clips 52 and 52', as will be understood from Figure 2. Guide rails 66 are provided and coact with the arms 56 of the clips 52 and 52' and are held in position by brackets 67 and reinforced by cross members 68.

The top edges of the side plates 7 and 8 opposite the turn table 18 are provided with cams 69 illustrated in Figures 1 and 2 as coacting with the arms 56 of the clips 51 and 51' to open these clips and permit the record to drop onto the turn table. The arms 57 of the clips 51 and 51' are held down at this time by means of guide brackets 70 fastened to the side plates and overlying the cams 69, as shown in Figures 6 and 16.

From the foregoing it will be understood that as the chains are driven the set of clips 50 and 50' is automatically opened to receive a record at the discharge end of the storage rack. At the proper time this set of clips 50 and 50' is released by the cams and grips the record to pick it up and carry it along with the chains. At the same time the set of clips 51 and 51' have picked up their record on the turn table and are returning to the storage rack. During this action the other active set of clips 52 and 52' have moved down past the receiving end of the storage rack and have been acted on by the cams 65 to release their record and deposit it in a pocket of the storage rack.

Transfer drive.

Means for driving the transfer chains is provided and comprises an electric motor 75 suitably supported on one of the side plates and having its armature shaft 75' coupled as at 76 to a worm shaft 77 having a worm 78 meshing with a worm wheel 79 fixed to a shaft 45 journaled in the side plate 7 and having a pinion 81 fixed thereto and meshing with an intermediate gear 82, the latter also being rotatably mounted on the side 7 and meshing with a driven gear 83 fixed to the shaft 47 on which the sprocket wheels 46 and 46' are mounted. In this way when the motor 75 is energized the sprocket chains are driven at a very slow rate from the armature shaft thereof.

Spring motor winding mechanism

Whenever the chains 41 and 42 are driven the spring motor 19 for driving the turn table is also wound and for this purpose a worm wheel 85 also meshes with the worm 78 and is fixed to a shaft 86 having a sprocket wheel 87 mounted thereon. The sprocket wheel 87 is connected to the shaft 86 through a slip clutch designated generally at 88 and comprising a disk 89 fixed to the shaft 86 and

having a felt facing or felt washer 90 interposed between it and a disk 91 rigidly connected to or formed integrally with the sprocket wheel 87. The disk 91 is pressed against the friction facing 90 and consequently toward the disk 89 by means of a spring washer 92 mounted on the shaft 86 and tensioned by means of a nut 93 threaded on the shaft 86 and engaging the washer 92, the nut 93 being locked in position by a set screw 94.

A sprocket chain 95 is trained over the sprocket wheel 87 and around a sprocket wheel 96 mounted on a shaft 97 geared to the spring motor as at 98. A conventional pawl and ratchet 99 prevents retrograde movement of the shaft 97.

Controls for transfer drive

As shown in Figure 7, the electric motor 75 is controlled by means of a main automatic switch designated generally at 100, a manually operable switch designated generally at 101 and an auxiliary automatic switch designated generally at 102.

The main automatic switch 100 includes 90 spring or blade contacts 100^a and 100^b, the contact 100^a connecting to one side of the motor through a wire 100'. The other contact 100^b of the switch 100 connects by a wire 101' to one of the terminals of the 95 manually operable switch 101. The other terminal of this switch 101 connects with one side P of the power line. The other side of the power line designated at P' connects to the other terminal of the motor 75. The 100 switch 102 is incorporated in a shunt path provided around the terminals of the manually operable switch 101, and for this purpose a wire 102' electrically connects one of the contacts 102^a of the switch 102 with the 105 power line P and a wire 103' connects the other contact 102^b of the switch 102 with the wire 101'. The manually operable switch 101 may be of any suitable type and may be controlled from a remote point. The contacts 102^a and 102^b are of the spring or blade type and when released automatically separate under the action of their spring carriers. Normally, however, these contacts 102^a and 102^b are held in engagement by a 110 spring biased operating device which may comprise a lever 103 fulcrumed on the panel and biased by a spring 104 to engage the contact 102^b and press it into engagement with the contact 102^a. The upper arm of 120 this operating lever 103 is designated at 104' and is disposed in the path of the lugs 155 provided on the grippers of the adjacent transfer chain, and when engaged by these grippers or by their lugs the lever 103 is 125 rocked against the action of the spring 104 to release the contacts 102^a and 102^b and permit them to disengage. As shown, the lever 103 is located to one side of the switch 100 and consequently it is rocked by the lugs on 130

the grippers of the adjacent transfer chain before these grippers approach the operating means for the main automatic switch 100, which is now to be described.

5 The contact 100^a is carried on but insulated from an operating lever 107 fulcrumed as at 107^a on a panel provided therefor on a side of the machine and having a coacting bell crank operating lever 108 associated therewith, the lever 108 being fulcrumed as at 109 on the panel and having its arm 108' cooperable with a notch 107' of the lever 107, the levers 107 and 108 are biased to proper position by means of a retractile coil spring 110 having its ends connected with the levers. The operating levers for the main automatic switch 100 are engaged and actuated by an operating pin 112 fixed to the tone arm 21 of the sound reproducer and partaking of the horizontal swinging motion thereof. The arrangement is such that when the reproducer has swung to the position that it occupies when the playing of a record is completed, the pin 112 will move over and engage an adjustable abutment 112^a provided on the lever 107 thereby swinging the lever 107 in a clockwise direction as viewed in Figure 7 to cause the contacts 100^a and 100^b to engage, thus completing the main path through and starting the motor provided the manually operable switch 101 is closed. When the motor is thus energized it drives the transfer chains to take the record from the turn table and return it to the storage station and to deposit a new record on the turn table. Before this transfer is effected, however, the reproducer is lifted away from the record and the turn table is stopped automatically 40 in a manner which will be hereinafter described.

Main cam control

As shown in Figure 5, the shaft 47 on which the sprocket wheels 44 and 44' are fixed, has a pinion 115 secured thereto, the pinion 115 meshing with a gear 116 rotatably fixed on a cam shaft 117 rotatably supported on the side plate 8. On this shaft 117 a main 50 cam 118 is secured and for the major portion of its extent its periphery is circular but at one portion is provided with a cam recess 119. A follower or cam lever 120 is pivoted as at 121 on the adjacent side plate 8 and has an angular end 122 provided with a roller 123 which engages the periphery of the cam 118. The upper end of this lever is pivotally connected to one end of a link 124, the other end of which link is pivotally connected as at 125 to a lifting lever 126 fulcrumed as at 127 to the side plate and having a curved lifting arm 128 engaging a roller 129 provided at the lower end of a leg 130 secured on an arm 131, rigidly connected to the fitting 24 of the sound reproducing mechanism.

When the cam 118 is turned and the follower is forced out of the recess 119 and onto the periphery of the cam the lever 120 is rocked in a clockwise direction as viewed in Figure 5 thus pulling the link 124 to the right and 70 swinging the lifting lever 128 to raise its curved arm to the dotted line position thereby swinging the arm 131 to elevate the reproducer as illustrated in dotted lines in Figure 6. This upward swinging movement of 75 the arm 131 brings it close under the turn table and causes a brake shoe 132 fixed on the arm 131 to engage the brake drum 133 constituted by the flange of the turn table thereby stopping the rotation of the turn table. 80

The lowering of the reproducer is cushioned by means of a dash pot designated generally at 134 and including a cylinder 135 carried by a bracket arm 136 fixed as at 137 to the side plate 8, and a piston 138 operates in the cylinder 135 and connected to a piston rod 139 having a pin and slot or other suitable connection 140 with the arm 131.

Shiftable top structure and operating mechanism therefor

For the purpose of aiding the transfer chains in holding the record above the turn table and above the centering pin during the transferring operations, a vertically shiftable top 141 is provided and consists of a plate flat for the major portion of its length and provided with down curved ends 142 conforming in their curvature to the curved path of the transfer chains at the corners of the machine. The plate 141 is carried by guide studs 143 which slide through bearing brackets 144 fixedly supported on the side plates. Compression coil springs 145 encircle the guide studs 143 and engage heads at the lower ends of the studs and also engage the brackets to bias the top 141 to its lowermost position. This lowermost position or inactive position is occupied whenever a record is being played but during the transferring operations the top is automatically elevated and for this purpose levers 146 are provided and are fixed to rock shafts 147 rotatably mounted on the side plates. The levers 146 have camming fingers 148 engaging the underside of the top plate 141. One of the levers 146 is connected by 110 means of a link 151 with the follower lever 120. A retractile coil spring 152 has one end anchored as at 153 on one of the side plates and has its other end connected as at 154 to one of the arms 149 and tends to swing the 115 levers 146 in a clockwise direction as shown in Figure 5 thereby pulling on the link 151 and tending to hold the follower 120 engaged with the cam 118. The springs 145 supplement the action of the springs 152 in this respect. 120

The top plate 141 has a central opening to accommodate the turn table.

Operation of main cam control and automatic switch

5 During the time a record is being played the contacts 100^a and 100^b are disengaged and the circuit for the motor 75 is broken so that the transfer chain remains stationary. In the same phase of the operation the roller 123 of the cam follower is positioned in the recess 119 of the cam 118 and the arm 131 is lowered to leave the tone arm 121 in its lowermost position and the turn table brake 132 released. The top 141 is also held down by its springs 145 at this time. When the playing of a record is completed the pin 112 swings the lever 107 to engage contacts 100^a and 100^b thereby closing the circuit through motor 75 and starting the transfer chains 41 and 42 in motion and rotating the main cam 118 to cause the roller 123 to ride up out of the recess 119 and onto the periphery of the cam 118 and consequently swinging the follower lever 120 in a clockwise direction as viewed in Figure 5. When the main cam 118 swings the follower lever 120 in a clockwise direction, as viewed in Figure 5, the arm 131 is raised to apply brake 132 and stop the turn table and simultaneously elevates the tone arm 21 and its sound box. The tone arm starts to rise before the brake is applied. At the same time the levers 146 are rocked to cause the camming fingers 148 and 148^a to raise the shiftable top 141. This occurs immediately after the transfer chains have been started and just before they have moved the clips 51 and 51' off of the cams 69. As soon as the clips move off of the cams 69 the lower clip arms 57 raise up and lift the record until the record engages the upper clip arms 55. The record is now positively held by the grippers and is carried along with the chains and over and down to the receiving end of the storage station. Simultaneously with this the clips 50 and 50' which have previously engaged the record at the discharge end of the storage station, move with the chains 41 and 42 to carry the record up over the raised top 141. As the record taken from the discharge end of the storage station is brought into position over the turn table one of a number of lugs 155 on the chain 42 engages the pin 112 on the tone arm to swing the tone arm and reproducer back to initial plane position. These lugs 155 are constituted by vertical extensions on the arms 56 of the clips 50', 51', 52' and 53', and in the phase of the operation shown in the drawings, the lugs 155 coacting with the pin 112 is formed on the clip 51'. This swing of the tone arm and its pin 112 causes the pin to strike the lever 108 of the switch to swing the lever 108 into the notch 107' of the lever 107 and permit the spring 110 to draw the levers 107 and 108

together thereby disengaging the contacts 101 and 102 and stopping the motor 75. At the same time the cam 118 has been so far rotated as to bring the recess 119 opposite the roller 123 of the follower permitting the roller 123 to snap into the recess under the influence of the springs 152 and 145 thereby throwing the lifting lever 128 downwardly to the full line position shown in Figure 5. This permits the tone arm to lower about its trunnions 25 and as it lowers the arm 131 swings with it disengaging the brake shoe 132 from the turn table to permit the turn table to rotate prior to the engagement of the stylus of the reproducer with the record on the turn table. The descent of the reproducer is cushioned by the dash pot to prevent injurious contact between the needle and the record. The record is then played and the tone arm traverses the record in the usual manner and when the playing of the record has been completed the same cycle of operations is repeated.

When ever the machine is operated for playing the plurality of records successively the manually operable switch 101 is closed and at such time the auxiliary automatic switch 102 has no effect whatsoever on the operation since it merely controls the shunted path around the manually operable switch. The primary control of the transfer drive resides in the switch 100 as whenever this switch is open the transfer motor circuit cannot be completed. Hence, even if both the manually operable switch 101 and the auxiliary automatic switch 102 are closed the transfer motor will not be operated unless and until the contacts 100^a, 100^b are closed. For this reason in describing the ordinary automatic operation of the machine the auxiliary automatic switch has been ignored and the manually operable switch assumed to be closed.

If now the manually operable switch 101 is opened while the record is being played, the playing of the record will be continued until the record is completely played. While the record is being played the gripper on the top run of the adjacent transfer chain has passed the operating lever 103 and consequently the lever 103 is released and biased with the spring 104 to press the contacts 102^a and 102^b of the auxiliary automatic switch 102 into engagement. It follows that when the playing of a record is completed the switch 102 is closed and as at this time the pin 112 closes the contacts 100^a, 100^b the transfer motor circuit will be completed notwithstanding the open condition of the switch 101 and the current flows from the power line P', through the motor and its field, through the wire 100', contacts 100^a and 100^b, wire 101', wire 103', contacts 102^a and 102^b, and wire 102', back to the other power line P. The consequent operation of the transfer motor causes the transfer chains to be driven, the

105

110

115

120

125

130

played record on the turn table to be picked up and carried on toward the receiving end of the storage rack and a new record to be carried from the discharge end of the storage rack toward the turn table. As the new record reaches a position immediately adjacent the turn table the lug 155 on one of its grippers engages the lever 103 and rocks the lever to permit the contacts 102^a and 102^b to separate thereby breaking the transfer motor circuit and stopping all operation. As before described, whenever the transfer chains begin to operate to effect the transfer operation, the main cam automatically applies the turn table brake and consequently all operations have now ceased.

To renew operation of the machine it is necessary to close the manually operable switch 101 and this causes the current to flow through the transfer motor, the current flowing from the power line P', through the motor and its field, and thence through the wire 100', contacts 100^a and 100^b, wire 101', and switch 101, back to the other power line P. Thus, the transfer motor 75 is again operated to drive the transfer chains and advance the record to the turn table on which it is deposited in the manner described. This movement of the record to the turn table repositions the reproducer and the repositioning of the reproducer involves a swinging of its pin 112 to open the contacts 100^a, 100^b and consequently break the transfer motor circuit. As long as the switch 101 is left closed the automatic operation continues.

Storage rack feed and guide

During the record transferring operation and in fact just shortly after a played record is moved off of the turn table, the storage rack is advanced to feed the next record to the discharge end of the storage rack and this advance is effected by means of a step by step motion associated with the storage rack and actuated by lugs 172 provided on the spring clips 50, 51, 52 and 53 carried by the transfer chain 41. As shown in Figures 9 and 10, each strip of the storage rack has a tooth 160 embedded therein and projecting down through the belt 31 into the slot 39^a (see Figure 8). With these teeth a pawl 161 coacts, the pawl being pivoted as at 162 on a crank arm 163 fixed to a rock shaft 164. A spring 165 is fixed to the crank arm 163 and engages a pin 166 on the pawl 161 to urge the pawl into engagement with the teeth 160. The shaft 164 has a gear wheel 167 fixed thereto and meshing with a pinion 168 pivotally mounted on the adjacent side plate and having an arm 169 fixed thereto and urged against a stop 170 by means of a spring 171. This arm 169 is disposed in the path of the lugs 172 and these lugs 172 periodically engage the arm 169 to rock it and thereby actuate the pawl 161 to advance the storage rack.

During their advance from the receiving end of the storage rack to the discharge end thereof, the records pass between longitudinal guides designated generally at 173 and 174. The guide 173 is fixed and has its ends 173' extended at right angles to the major portion of the guide and riveted or otherwise suitably fastened to the low cross members 68 which reinforce the guide rail 61 for the clips at the ends of the frame.

The guide 174 has the form of an elongated plate and is hingedly supported as at 175 on the frame. The hinges 175 may be spring hinges or if desired separate springs may be employed for the purpose of urging the guide 174 over into cooperative relation with the records. By swinging the guide 174 in a counter-clockwise direction, as viewed in Figure 1, it is disengaged from the records in the storage rack and this permits of the removal of the records from or the placing of records in the storage rack. The opening of the side plate 7 is sufficiently large to comprehend the entire extent of the upper run of the storage rack so that the filling of the storage rack to its full capacity with records as well as the removal of all of the records therefrom is facilitated.

Separator and guide for returned records

When the records are returned to the storage rack they pass down over a guiding and separating finger 180 mounted on a rock shaft 181 and automatically operated from the lifting fingers to the top plate by means of a link 183 pivotally connected to a crank arm 184 carried by the rock shaft 181 and a crank arm 185 fixed to one of the rock shafts 147. The finger 180 overlies the records in the storage rack and the record being lowered into the storage rack is prevented from fouling the records already therein as it slides down over the finger 180 and into its proper pocket. At this time the top plate 141 is held elevated and when it lowers the motion of its lifting fingers is transmitted to the guide finger 180 to lift it over the record last placed in the storage rack.

Centering means for record

When the record is released by the grippers for deposit on the turn table it is usually centered right over the pin of the turn table and drops into position without any difficulty but in some instances the record, during the time it is being lifted or gripped, may become slightly displaced downwardly and as a consequence its center hole lies to the left of the turn table as viewed in Figure 2. To insure proper positioning of the record on the turn table under such circumstances, a pair of centering fingers 190 are provided and are fixed to a rock shaft 191 journaled in the side plates and having a crank arm 192 fixed to one end thereof exteriorly of the side

plates. This crank arm 192 connects by a link 193 to a rocking lever 194 fulcrumed as at 195 on the side plate. A spring 196 coacts with the lever 194 to urge it to such a position as to swing the fingers 190 down below the top 141. The fingers 190 pass through slots 197 in the top 141. The lugs 172 provided on the chain 41 engage the laterally offset end of the lever 195 at the proper time to move it to operate the centering fingers.

Summary of the operation

From the foregoing it will be understood that the pin 112 swings horizontally with the tone arm, and closes the switch controlling the circuit to the motor 75 to start the drive for the transfer chains when the playing of a record has been completed. This also sets the main cam in motion. The main cam 118 operates at this time to elevate the tone arm 21 and apply the turn table brake 132 and it also elevates the table top 141. This action of the main cam occurs just before the motion of the transfer chains 41 and 42 has moved the clips 51 and 51' off of their cam 69. Just as soon as the arms 56 of these clips 51 and 51' move off of the cam 69 the clips grip the record and lift it up slightly and then carry it along with the transfer chains 20 toward the receiving end of the discharge station. During this movement of the transfer chains the clips 50 and 50' which have previously gripped the record at the discharge end of the storage rack carry their record up over the top 141 and along the same until their record overlies the turn table. As the clips 50 and 50' approach the turn table with their record the lug 155 of the clip 51' engages the pin 112 and swings the pin and tone arm connected thereto until the tone arm is returned to initial playing position. As the tone arm approaches the initial playing position the pin 112 moving therewith engages the lever 108 of the switch to break 45 the motor circuit and stop the transfer drive. At this time the cam 118 has completed a revolution so that the roller 123 again snaps into the recess 119 thus permitting the tone arm to lower onto the record and releasing the turn 50 table brake to permit the spring motor to drive the turn table. Simultaneously, with the release of the brake and the release of the tone arm for lowering the top 141 is permitted to lower.

55 As the clips 50 and 50' approach the turn table with their record the clips 53 and 53' are traveling up the runs of the chains 41 and 42 located on the opposite sides of the discharge end of the storage rack and after being spread to pass over the edges of the record at the discharge end of the rack 30 are released by the cam 65 and grip the record and elevate it slightly. These clips 53 and 53' hold the record in this position until the 60 next operation when they advance the record

to the turn table. The clips 51 and 51' which carry the record from the turn table back to the receiving end of the storage rack in the cycle of the operation shown and described are stopped in a position just above their cams 70 65 when the clips 50 and 50' have deposited their record on the turn table and the lug 155 on the clip 50' has stopped the transfer drive. In this position the lower edge of the record is located above the tops of the transverse strips 34 of the storage rack and this permits the storage rack to be advanced without fouling the record carried by the clips 51 and 51'. The advance of the storage rack is effected as described by the lug 172 of the clip 53 shortly after the clips 51 and 51' move off of the turn table with their record.

The invention claimed is:

1. An apparatus for playing a plurality of records comprising record playing means, a storage station for the records, transfer means for taking a record from the storage station and transferring it to the record playing means and vice versa, a drive for the transfer means, means controlled by the record playing means when the playing of a record is completed to start said transfer drive and directly controlled by the record playing means when the parts thereof are positioned to initiate the playing of a record to 90 stop said transfer drive, and means controlled by the transfer means for moving the parts of the record playing means to initial playing position upon completion of a record transfer operation.

2. An apparatus for playing a plurality of records comprising record playing means, a storage station for the records, transfer means for taking a record from the storage station and transferring it to the record playing means and vice versa, a drive for the transfer means, means controlled by the record playing means when the playing of a record is completed to start said transfer drive and directly controlled by the record playing means when the parts thereof are positioned to initiate the playing of a record to 95 stop said transfer drive, means controlled by the transfer means for moving the parts of the record playing means to initial playing position upon completion of a record transfer operation, and means operated in synchronism with the transfer means for starting and stopping the record playing means.

3. An apparatus for playing a plurality of records comprising record playing means, a storage station for the records, transfer means for taking a record from the storage station and transferring it to the record playing means and vice versa, a drive for said transfer means, means controlled by the record playing means when the playing of a record is completed to start said transfer drive and directly controlled by the record playing means when the parts thereof are 125 130

- positioned to initiate the playing of a record to stop said transfer drive, means for automatically shifting the parts of the record playing means to position to initiate playing of a record when a new record is transferred to the turn table, and means controlled by the transfer means for advancing the records in the storage station each time a record is transferred and during a transferring operation.
10. An apparatus for playing a plurality of records comprising record playing means including a motor driven turn table, an arm traversing the turn table, and a control regulating the starting and stopping of the turn table, a storage station for the records, transfer means for taking a record from the storage station and transferring it to the turn table and vice versa, an electric motor driving the transfer means, a switch controlled by said arm for causing said motor to start and stop, means operated in synchronism with the transfer means for raising and lowering said arm and for operating the control for the turn table to start and stop the turn table, means carried by the transfer means for swinging the arm, when elevated, to initial playing position.
5. An apparatus for playing a plurality of records comprising record playing means including a turn table, an arm traversing the turn table, and a control for the turn table, an endless storage rack for the records, transfer means for taking a record from the storage rack and transferring it to the turn table and vice versa, an electric motor for driving said transfer means, a switch controlled by said arm for causing said motor to start and stop, means operated in synchronism with the transfer means for raising and lowering said arm and for operating the control for the turn table, means carried by the transfer means for swinging the arm, when elevated, to initial playing position, and mechanism actuated by the transfer means for advancing the storage rack.
6. An apparatus for successively playing a plurality of records comprising a record storage station, a turn table, sound reproducing means cooperable therewith, transfer means for taking a record from the storage station and transferring it to a turn table and for simultaneously taking a record from the turn table and returning it to the storage station, a drive for said transfer means, a control for said transfer drive governed in its action by the sound reproducing mechanism and influenced thereby to start the transfer drive when the playing of a record is completed, and means cooperable with said control for stopping the transfer drive upon completion of a record transferring operation.
65. An apparatus for successively playing a plurality of records comprising a storage
- station for the records, a turn table on which the records are played, sound reproducing mechanism adapted to coact with records on the turn table, a control regulating the drive of the turn table, means for raising and lowering the sound reproducing mechanism, transfer means for taking a record from the storage station and transferring it to the turn table and for taking a record from the turn table and returning it to the storage station, a transfer drive for actuating said transfer means, a control for said transfer drive governed in its action by the sound reproducing mechanism and influenced thereby to start the transfer drive when the playing of a record is completed, means cooperable with the transfer drive control for stopping the transfer drive upon completion of a record transferring operation, and a single cam operated in synchronism with the transfer means for controlling the operation of the raising and lowering means and the operation of the turn table drive control.
8. An apparatus for successively playing a plurality of records comprising a storage station for the records, a turn table on which the records are played, sound reproducing mechanism adapted to coact with records on the turn table, a control regulating the drive of the turn table, transfer means for taking a record from the storage station and transferring it to the turn table and for taking a record from the turn table and returning it to the storage station, a transfer drive for actuating said transfer means, a control for said transfer drive governed in its action by the sound reproducing mechanism and the transfer means and influenced thereby to start the transfer drive when the playing of a record is completed and to stop the transfer drive when a record transferring operation is completed, and means operated in synchronism with the transfer means for controlling the operation of the turn table drive control.
9. An apparatus for successively playing a plurality of records comprising a storage station for the records, a turn table on which the records are deposited for playing, sound reproducing mechanism adapted to coact with the records deposited on the turn table, a plurality of sets of grippers positively engageable with the records and simultaneously operable for transferring a record from the storage station to the turn table and from the turn table back to the storage station, and means for automatically shifting said grippers.
10. An apparatus for playing a plurality of records comprising a turn table, a reproducer cooperable therewith, a storage rack located below the turn table, a flexible and endless transfer device extending past the receiving and the discharge ends of the storage rack and past the turn table, spaced sets

5 of grippers carried by the transfer device and engageable with the records for transferring them from the rack to the turn table and vice versa, and fixed and spaced cams cooperable with the grippers at the receiving and discharge ends of the rack and at the turn table for causing the grippers to engage and release the records automatically at the proper times.

10 11. An apparatus for successively playing a plurality of records comprising a storage station for the records, a turn table on which the records are deposited for playing, sound reproducing mechanism adapted to coact

15 with the records deposited on the turn table, and a single set of endless transfer devices for simultaneously carrying a record from the storage station to the turn table and back from the turn table to the storage station.

20 12. An apparatus for successively playing a plurality of records comprising a storage station for the records, a turn table on which the records are deposited for playing, sound reproducing mechanism adapted to

25 coact with the records deposited on the turn table, a single set of endless transfer members cooperably disposed with respect to the storage station and with respect to the turn table, spaced sets of grippers carried by the

30 endless transfer members and operable to grip a record in the storage station and transfer it to the turn table and to grip a record on the turn table and return it to the storage station, respectively, and means for automatically shifting the endless transfer members when the playing of a record has been completed.

35 13. An apparatus for successively playing a plurality of records comprising a storage station for the records, a turn table on which the records are deposited for playing, sound reproducing mechanism adapted to coact with the records deposited on the turn table, and a single set of endless transfer chains

40 having means acting to lift a record from the turn table and return it to the storage station and to simultaneously transfer a record from the storage station to the turn table, all upon the completion of the playing of 45 the record on the turn table.

50 14. An apparatus for successively playing a plurality of records comprising a storage station for the records having a receiving end and a discharge end, a turn table on

55 which the records are successively deposited for playing, sound reproducing mechanism adapted to coact with the records deposited on the turn table, and an endless transfer device for successively taking records from 60 the discharge end of the storage station and transferring them to the turn table for playing and for successively taking played records from the turn table and returning them to the receiving end of the storage station.

65 15. An apparatus for successively playing

a plurality of records comprising a storage station for the records having a receiving end and a discharge end, a turn table on which the records are successively deposited for playing, sound reproducing mechanism 70 adapted to coact with the records deposited on the turn table, a transfer device including an endless carrier extending in operative relation to the discharge and receiving ends of the storage station and also to the turn 75 table, spaced sets of grippers on said carrier, and means for causing the grippers to engage and disengage the records at the proper time in the cycle of operation.

16. An apparatus for successively playing 80 a plurality of records comprising a storage station for the records, a turn table, sound reproducing means cooperable therewith, and a single transfer means for transferring a played record from the turn table to the storage station and for simultaneously transferring another record from the storage station to the turn table.

17. An apparatus for successively playing 90 a plurality of records comprising a record storage station, a turn table, sound reproducing means cooperable therewith, endless transfer chains disposed in operative relation to the storage station and turn table, sets of spring clips carried by said chains and 95 adapted to grip the records, and means for opening said clips to permit them to grip and release the records at the proper time.

18. An apparatus for successively playing 100 a plurality of records comprising an endless storage rack for the records, a turn table, sound reproducing means cooperable with the turn table, a pair of endless transfer members cooperatively disposed with respect to the storage rack and turn table, spaced sets 105 of grippers carried by the endless transfer members and adapted to grip the records, and means for causing the grippers to engage and release the records at the proper times.

19. An apparatus for successively playing 110 a plurality of records comprising an endless storage rack for the records, a turn table, sound producing means cooperable with the turn table, a pair of endless transfer members cooperatively disposed with respect to the storage rack and turn table, spaced sets of 115 grippers carried by the endless transfer members and adapted to grip the records, means for causing the grippers to engage and release the records at the proper times, and means for advancing the storage rack each time a record is taken from the turn table.

20. An apparatus for playing a plurality 120 of records including a storage rack comprising an endless belt and transverse strips secured to the belt and providing record pockets, and means for advancing the storage rack including a tooth engaged with each strip and projecting in through the endless belt to the interior thereof, a pawl cooperable with 125

the tooth and means for intermittently actuating the pawl.

21. An apparatus for playing a plurality of records comprising a turn table, a repro-

- 5 ducer cooperable therewith, an endless storage rack located below the turn table, a pair of flexible endless transfer members having runs extending past the opposite sides of the turn table and runs extending past the opposite sides of the storage rack at the ends thereof, and grippers carried by the transfer members and positively engageable with the records for transferring the records from the storage rack to the turn table and from the turn table back to the storage rack.

10 22. An apparatus for playing a plurality of records comprising a turn table, a reproducer cooperable therewith, an endless storage rack located below the turn table, a pair of flexible endless transfer members having runs extending past the opposite sides of the turn table and runs extending past the opposite sides of the storage rack at the ends thereof, and grippers carried by the transfer members and positively engageable with the records for transferring the records from the storage rack to the turn table and from the turn table back to the storage rack, a vertically shiftable top arranged between the runs of the transfer members extending past the turn table and aiding the transfer chains in holding the record above the turn table during the transfer operation and means for raising the top during the record transferring operations and for lowering the top when a record is being played.

15 25 30 35

23. An apparatus for playing a plurality of records comprising a turn table, means for rotating the turn table, a reproducer cooperative therewith, supporting means for the reproducer permitting it to swing horizontally and vertically, a storage station for the records, record transfer means between the storage station and the turn table, an arm connected to the supporting means and constraining the same to partake of the vertical swinging movement thereof, a brake for the turn table operated by the arm and effective to regulate the starting and stopping of the turn table, and means for raising the arm when the playing of a record is completed and for lowering the arm when a new record is deposited on the turn table in position for playing.

55 24. An apparatus for playing a plurality
of records comprising a turn table, means for
rotating the turntable, a reproducer coopera-
ble therewith, supporting means for the re-
producer permitting it to swing horizontally
60 and vertically, a storage station for the
records, record transfer means between the
storage station and the turn table, an arm
connected to the supporting means and con-
straining the same to partake of the vertical
65 swinging movement thereof, a brake for the

turn table operated by the arm and effective to regulate the starting and stopping of the turn table, means for lifting the arm to elevate the tone arm and apply the brake, and a dash pot for retarding the lowering of the arm whereby the turn table acquires appropriate speed of rotation before the reproducer engages the record.

25. An apparatus for playing a plurality of records, comprising record playing means, a storage station for the records, transfer means for taking the record from the storage station and transferring it to the record playing means and vice versa, an electric motor for driving the transfer means, a circuit for said motor, a main automatic switch and a manually operable switch incorporated in said circuit, said circuit having a shunt path around said manually operable switch, an auxiliary automatic switch incorporated in said shunt path, means operated by the record playing means for controlling the main automatic switch, and means operated by the transfer means for controlling the auxiliary automatic switch. 75 80 85 90 95

In witness whereof, I hereto affix my signature.

CARL L. FERGUSON.
